DESIGN FOR A LAMP BREAK

Edward Hesly, Chicago, Ill., assignor to Rembrandt Lamp Corporation, Chicago, Ill., a corporation of Illinois

Application June 21, 1947, Serial No. 139,862

Term of patent 14 years

(Cl. D48—20)

To all whom it may concern:

Be it known that I, Edward Hesly, a citizen of the United States, residing in Chicago, in the county of Cook and State of Illinois, have invented a new, original, and ornamental Design for a Lamp Break, of which the following is a specification, reference being had to the accompanying drawings, forming part thereof, in which:

Fig. 1 is a front elevational view of one side of a lamp break embodying my new design;

Fig. 2 is a side elevational view thereof; and

Fig. 3 is a top plan view thereof.

I claim:

The ornamental design for a lamp break, substantially as shown.

EDWARD HESLY.
